(57) CLAIM

The ornamental design for handbag, as shown and described.

DESCRIPTION

FIG. 1 is a front perspective view of a handbag showing my new design;

FIG. 2 is a front view of the handbag shown in FIG. 1;

FIG. 3 is a rear view of the handbag shown in FIG. 1;

FIG. 4 is a right side view of the handbag shown in FIG. 1 (with the left side view being a mirror image thereof);

FIG. 5 is a top view of the handbag shown in FIG. 1;

FIG. 6 is a bottom view of the handbag shown in FIG. 1;

FIG. 7 is a front perspective view of an alternative embodiment of the handbag shown in FIG. 1;

FIG. 8 is front view of the alternative embodiment of the handbag shown in FIG. 7;

FIG. 9 is a rear view of the alternative embodiment of the handbag shown in FIG. 7;

FIG. 10 is a right side view of the alternative embodiment of the handbag shown in FIG. 7 (with the left side view being a mirror image thereof);

FIG. 11 is a top view of the alternative embodiment of the handbag shown in FIG. 7; and,

FIG. 12 is a bottom view of the alternative embodiment of the handbag shown in FIG. 7.

The broken line showing of the handle, buckles, and jewel piece is for illustrative purposes only and forms no part of the claimed design.
